UNITED STATES PATENT OFFICE.

GEORGE ROBERT CONNALLY, OF SHANNON, MISSISSIPPI.

DESIGN FOR AN ATTACHMENT FOR GRATES.

SPECIFICATION forming part of Design No. 29,442, dated October 4, 1898.

Application filed September 2, 1898. Serial No. 690,138. Term of patent 14 years.

To all whom it may concern:

Be it known that I, GEORGE ROBERT CONNALLY, a citizen of the United States, residing at Shannon, in the county of Lee and 5 State of Mississippi, have invented and produced a new and original Design for Attachments for Grates; and I do hereby declare the following to be a full, clear, and exact description of the same, reference being had to 10 the accompanying drawings, forming a part thereof.

In the accompanying drawings, Figure 1 is a perspective view of an attachment for an open grate embodying my design and looking 15 at the same from above, and Fig. 2 is a perspective view of the grate attachment embodying my design and looking at the same from beneath.

The leading feature of my design consists 20 of a horizontal supporting-shelf, rearwardly and downwardly extending lugs, and forwardly and downwardly extending legs, which form, with the rearwardly and downwardly extending lugs, apertures for the reception of 25 one of the front bars of an open-place grate.

A in the drawings represents my attachment for an open-place grate embodying my design, which comprises in its construction an elongated horizontal supporting-surface a , which is provided on its under side with rearwardly and downwardly extending lugs a' and with long forwardly and downwardly extending legs a^2 , which legs, with the lugs a' , form apertures a^3 for the reception of one of the front bars of a grate, the forwardly and 30 downwardly extending legs a^2 being of sufficient length to bear upon a lower front grate-bar when the attachment is in position on the grate. 35

Having now described my invention, what 40 I claim as new, and desire to secure by Letters Patent, is—

The design for an attachment for a grate, substantially as herein shown and described.

In testimony whereof I hereunto affix my 45 signature in presence of two witnesses.

GEORGE ROBERT CONNALLY.
